LIGHTING UNIT FOR RANGES

Donald L. Hadley and Edwin H. Lockwood, Mansfield, Ohio, assignors to Westinghouse Electric & Manufacturing Company, East Pittsburgh, Pa., a corporation of Pennsylvania

Application May 29, 1936, Serial No. 82,430

3 Claims. (CL 240—2)

This invention relates to cooking ranges and particularly to electrically heated ranges.

It is an object of this invention to provide convenient means for the illumination of the range.

It is a further object of this invention to locate the indicating and control devices near together and to provide for their illumination by lamps conveniently located with respect to the grouped devices.

It is a further object of this invention to provide a rotatable support for each lamp whereby the lamps may be individually moved in position to illuminate the control devices or to illuminate the part of the stove which is being used.

The invention also contemplates a clock mounted at the upper part of the range and strongly illuminated by said lamps when they are in the position in which they are normally kept.

The invention also contemplates a range in which the top is divided into a cooking area equipped with heaters and a working area free from heaters. It is an object of said invention to provide for the selective illumination of one part of the top or the other.

It is also an object of this invention to provide for general illumination of the kitchen from the lamps when in appropriate position.

Other objects of the invention and details of construction will be apparent from the following description and the accompanying drawings, in which:

Figure 1 is a front elevational view of the range equipped with its lamps.

Fig. 2 is a side elevational view of the same.

Fig. 3 is a plan view showing the lamps in their normal position.

Fig. 4 is a plan view showing the lamps in a rotated position.

Fig. 5 is a front elevational view of one lamp and its support.

Fig. 6 is an end elevational view of the same, and

Fig. 7 is a detailed view showing the method of securing the lamp support to the range.

The range 1 is of cabinet form and consists of a cabinet proper having a top 2 and a back-splasher 3 projecting from the rear edge of the top in a familiar way. The back-splasher comprises a front wall 4 and a top 5. The front wall 50 is bent toward the back at each end forming closures for the end. The back-splasher is thus in effect a hollow structure although if desired it may be open on the side that is toward the wall of the kitchen.

Various devices for controlling, indicating or

otherwise facilitating the use of the range are gathered together in the back-splasher. As illustrated, they include a row of switches 8 and various indicating devices such as lamps to show whether the oven heaters are working and devices to show the temperature in the oven, etc. One such temperature indicating device is shown at 9. These devices either project through openings in the front wall or illuminate windows therein.

Devices are provided in the back-splasher through which the time at which heat will be turned off is controlled. Indicators of such time are provided, preferably, adjacent the face of a time clock 10 mounted on the top of the back-splasher. The usual ovens and warming closets are provided in the body of the cabinet. The top 2 of the cabinet has a space 12 free from heating plates which is for the operator to use as a table. The other part of the top surface 2 is provided with heating plates 14, which the operator may use for cooking.

On each side of the center of the back-splasher an illumination device 15 is mounted. The following description of one of said illumination devices applies equally to each of them. Preferably it consists of a shade 16 covering a lamp 17 (Figs. 5 and 6) which is mounted in a lamp socket 18 and controlled by a pull chain 19. The shade 16 is open at the bottom, as indicated by the dotted lines, showing the thickness of the side and end walls. An additional opening is shown at 22. It is located in that end wall of the shade which is most remote from the tubular shaft 23 upon which the shade is supported. The shade is secured to this shaft, as indicated at 25. Between the shaft proper and the portion to which the shade is attached a right-angle bend 26 is provided so that the long dimension of the shade is horizontal although the shaft is vertical.

Wires 28 extend through the shaft from any suitable power connection to the lamp 17 and to a socket 27 which forms one member of a separable connection. The second member of this separable connection is not shown. It is intended to secure a cord to the socket 27, which cord can pass over the back-splasher to the space between the range and the kitchen wall and extend to any device which it is desired to furnish with power, such as a toaster or percolator. Wires 29 from the socket 27 extend through a tube 28 which forms a continuation of the shaft 23. At one point wires branch from this tube and are connected to the lamp socket 18.

In the back-splasher brackets 30 are provided,

which are secured to the top wall of the back-splasher, preferably by spot welding flanges 31 which are a part of the bracket. The flanges 31 are united by a U-shaped member which is the bracket proper. The bottom of the U-shaped member has a hole 33 for the reception of a tube 35. The lower end of this tube is provided with a flange 37 by which it is secured to the bracket in any suitable manner, preferably by bolts 38. 10 The tube is thus secured in an upstanding position. Its upper end is above the top wall of the back-splasher which is provided with a hole for the combination of the tube.

The tube is of suitable diameter to receive the 15 end of the shaft 23. This shaft is equipped with a pin 38 secured therein in any desired manner, preferably by providing the wall of the shaft 23 with two diametrically opposite holes through one of which the pin 39 projects and through the 20 other of which a reduced end of the pin, as shown at 40, extends. The exterior end of the end of the reduced part 40 is expanded, by spinning or in any other desirable way, to secure the pin 39 in the shaft 23.

25 When the shaft is entered into the tube 35, the pin 39 passes through the open end 41 of a T-shaped slot, the bottom of the stem of the T being at the top of the tube. The cross part of the T constitutes a horizontal portion 42 of the slot. 30 The pin 39 passes through the vertical portion 41 of the slot and is received in the horizontal part 42. The shaft 38 is then rotated until the pin contacts one end of the horizontal portion 42 of the slot. This brings the illumination device 15 35 carried by the shaft into the position illustrated in Fig. 3. This is the position normally occupied by the device before the operator rotates it.

In this position, light from the lamp 17 passes 40 through the end of slot 22 and illuminates the face of the clock 10. There being two of the illumination devices, the clock 10 is illuminated from both sides and light is reflected therefrom in all directions so that the clock is easily read from any part of the kitchen. In this position 45 of the illuminating device, the bottom of the shade 16 permits light from the lamp 17 to descend upon the front wall 4 of the back-splasher. 3. The devices projecting through the wall 4 are thus well illuminated.

50 When the range is being used as a table, the left-hand device 15 illuminates the work space 12. The operator may, therefore, move the left-hand device 15 into the position illustrated in Fig. 4 for convenience in working on the table. 55 If the operator is cooking anything on the top of the range, the right-hand device 15 may be swung in the position illustrated in Fig. 4 for convenient inspection of the contents of the cooking vessels. If desired, both lamps may be rotated as illustrated in Fig. 4, thus illuminating 60 both the table surfaces and the cooking surface. When the illumination of the top of the range is not needed, the lamps may be moved into the position shown in Fig. 3 where they illuminate 65 the clock and the kitchen generally.

When it is desired to use a percolator, a toaster or other auxiliary heat device, the cord from such device may be connected to a plug and the plug inserted into the socket 27. This connection may be made in any position of the shaft 23 and the 5 cord will extend over the back-splasher and down behind it and to the auxiliary device located in any convenient place. If, afterward the lamp fixture 15 is moved forward the cord will be dragged over the back-splasher and will connect 10 to the socket 27 in any position of the fixture 15. If the fixture is pushed back toward the back-splasher the cord will be dragged down by the weight of the part behind the back-splasher and will slide over the top edge thereof as the lamp 15 fixture approaches. Thus the cord is not in the way at any time although energized by permanent connection 28 within the fixture.

Many modifications will occur to those skilled in the art and we do not desire to be restricted 20 to the exact details shown and described. The intentional limitations are stated in the claims.

We claim as our invention:

1. Apparatus comprising a hollow rear instrument-supporting panel having front and top walls, 25 a bracket therein secured to and depending from the top wall, a tube secured to said bracket, a shaft carried in said tube for rotation about the axis of the tube, said shaft having a stop on the side thereof, a slot in said tube cooperating with said 30 stop to limit the rotation of said shaft, said tube having a second slot extending lengthwise to the end thereof and permitting said stop to be received with the first named slot, and a lamp carried by said shaft at one side thereof. 35

2. Apparatus comprising a hollow rear instrument-supporting panel having front and top walls, a bracket within said panel, said bracket comprising a U-shaped member, the upper ends of the legs of said member being bent to extend 40 parallel to and being secured to said top wall, a tube having a flange on its end, fastening means securing said flange to said bracket and thus securing the tube in a vertical position within the panel, and a lamp supporting shaft rotatably 45 mounted in said tube.

3. Apparatus comprising a hollow rear instrument supporting panel having front and top walls, a bracket within said panel, said bracket comprising a U-shaped member, the upper ends 50 of the legs of said member being bent to extend parallel to and being secured to said top wall, a tube having a flange on its end, said tube extending through the bottom of said U-shaped member, fastening means securing said flange to said 55 bracket and thus securing the tube in a vertical position within the panel, and a lamp supporting shaft rotatably mounted in said tube, the upper end of said tube extending above the top of the panel and having a slot, and a stop on said 60 shaft cooperating with said slot to limit the rotation of the shaft.

DONALD L. HADLEY.
EDWIN H. LOCKWOOD.
